Primary Examiner — Marie D. Fast Horse*Assistant Examiner* — Jennifer Sierra Yosinski(74) *Attorney, Agent, or Firm* — John Rizvi; John Rizvi, P.A.—The Patent Professor ®(57) **CLAIM**

The ornamental design for a sponge holder as shown and described.

DESCRIPTION

FIG. 1 is a front isometric view of a sponge holder showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front isometric view of the sponge holder, shown in a state of use with an environmental sponge. The broken lines showing the sponge depict environment that forms no part of the claimed design, and are for the purpose of illustrating how the sponge fits onto the sponge holder.
